UNITED STATES PATENT OFFICE.

WITT JUNIPER, OF DETROIT, MICHIGAN.

VENTILATING-WINDOW FOR MOTOR-VEHICLES.

1,364,114.

Specification of Letters Patent.

Patented Jan. 4, 1921.

Application filed November 26, 1919. Serial No. 340,874.

To all whom it may concern:

Be it known that I, WITT JUNIPER, citizen of the United States, residing at Detroit, county of Wayne, State of Michigan, have 5 invented a certain new and useful Improvement in Ventilating-Windows for Motor-Vehicles, and declare the following to be a full, clear, and exact description of the same, such as will enable others skilled in 10 the art to which it pertains to make and use the same, reference being had to the accompanying drawings, which form a part of this specification.

My invention relates to windows for automobile curtains, shown in the accompanying drawings and more particularly described in the following specification and claims.

One of the objects of my invention is to provide a removable window for the side 20 curtains of the usual touring type of automobile top, though it may however be used in connection with a "winter" or other form of top.

Another object of the invention is to provide a construction in which the window may 25 be opened to a greater or less extent for ventilating purposes.

Another feature of the invention is the window supporting frame and means for 30 securing it to the surrounding curtain.

Another feature of the invention is the means employed to secure the "light" in the frame in which it is mounted.

Another object of the invention is that in 35 the event of the "light" being broken it may be replaced by anyone at a nominal cost without the necessity of employing skilled labor.

With the foregoing and other objects in 40 view which will appear as the description proceeds the invention consists in the combination and arrangement of parts and in the details of construction hereinafter described and claimed, it being understood that changes 45 may be made in the precise embodiment of the invention herein disclosed without departing from the spirit of the same.

In the accompanying drawings forming part of this specification:—

50 Figure 1 is a side elevation of a fragmentary part of an automobile top, showing one of the windows partially open for purposes of ventilation.

Fig. 2 is a side elevation of the metal sash 55 frame with the "light" in position, showing

the auxiliary metal strip for securing the light when lodged in the frame.

Fig. 3 is a view of the opposite side of the sash frame.

Fig. 4 is a fragmentary perspective view 60 of the side curtain and supporting frame for the sash, showing the manner of securing the frame to the surrounding wall of the curtain.

Fig. 5 is a sectional view through the window sash on line 5—5 of Fig. 2.

Fig. 6 is a detail cross-sectional view taken on or about line 6—6 of Fig. 1, showing the manner of securing the sash supporting frame to the curtain,—also the sash 70 frame as it would appear in place.

Fig. 7 is an elevation of the window and frame as viewed from the inside of the curtain.

Fig. 8 is a perspective view of the corner 75 piece employed in connection with the supporting frame, as indicated in dotted lines in Fig. 7, to cover the ends of the tie wire and for giving the frame a more finished appearance.

Referring now to the letters of reference placed upon the drawings:—

A, denotes the body of a motor vehicle, B, its top and C its removable side curtains.

D, indicates a window supporting frame 85 formed of sheet metal and secured to the wall of the removable curtains.

The sheet metal frame D, is constructed with return bends D', D' to receive the curtain wall C', and a cord or wire E, around 90 which the curtain is folded and also lodged in the bends, which are afterward compressed to impinge upon the curtains as shown in Fig. 6. The ends of the wire E, which encircle the frame to secure the curtain therein are twisted together as indicated at E' to insure against dislodgment.

F, indicates a corner strip having return folds F', designed to overlap the edge of the frame to conceal the twisted ends of the wire 100 and to give the frame a more finished appearance at the several corners thereof, as clearly indicated in dotted lines in Fig. 7.

D², designates a return bend in the frame D,—spaced from the folded portion D', 105 overlapping the outer surface of the curtain,—to receive a sheet metal frame G, for supporting a sheet of glass H, or other transparent medium.

The frame G is of channel form in cross 110

section,—one end or side being preferably narrower (as indicated at G') than its opposing wall G², in order that the glass or celluloid may be readily inserted in the 5 grooves formed by the sides of the frame. When the glass is in position, an auxiliary strip of metal G³, is inserted in the groove of the frame so as to overlap the edge of the glass—thereby securing the latter against 10 dislodgment,—as clearly indicated in Fig. 5 of the drawing.

In the event of the glass being broken, the fractured light may be readily removed and another sheet of glass inserted at small cost 15 without the necessity of employing skilled labor.

As indicated in Figs. 1 and 7 of the drawings the window sash may be pushed to one side in the supporting frame to provide any 20 desired degree of ventilation that may be desired.

Having thus described my invention what I claim is:—

1. In a curtain for a vehicle top; a sheet 25 metal frame having return bends to receive the curtain; a wire encircling the frame between the return bends, around which the wall of the curtain is folded to secure the curtains to the frame; said frame having 30 also another return bend adapted to receive a sash frame, and a removable sash frame slideable in said last named frame to provide various sized vent openings.

2. In a curtain for a vehicle top, a sheet metal frame having return bends to receive 35 the curtain, a wire carried by the curtain the edges of the curtain being folded to inclose the wire, the ends of the wire being twisted together, the edges of the curtain thus wired fitting in the return bends of the sheet metal 40 frame whereby the sheet metal frame and the curtain are secured together, said frame having also another bend adapted to form a guide for a sash frame, a corner piece adapted to fit over one corner of the 45 first mentioned frame to conceal the twisted ends of the wire, and a removable sash frame slideable in said first mentioned frame to provide various sized ventilating openings.

3. In a curtain for a vehicle top, a sheet 50 metal frame having return bends to receive the curtain, means whereby the curtain and frame may be secured firmly together the frame having other return bends, and a removable sash frame slideable longitudinally 55 in said other return bends of the first mentioned frame and entirely removable therefrom in a direction longitudinally thereof and also movable to provide various sized ventilating openings.

In testimony whereof, I sign this specification in the presence of two witnesses.

WITT JUNIPER.

Witnesses:

S. E. THOMAS,
EDWIN R. MONNIG.
